FASTENER-APPLYING DEVICE

Arthur H. Maynard, Warwick, and Joseph M. Gambao, East Greenwich, R. I., assignors to Boston Wire Stitcher Company, Warwick, R. I., a corporation of Maine

Application July 9, 1938, Serial No. 218,358

7 Claims. (Cl. 1-3)

This invention relates to improvements in fastener-applying devices adapted for attaching papers and other sheets, securing tags and labels to articles of commerce and for use generally in fastening or stitching together various objects and articles.

One object of the invention is to provide an implement of the type indicated adapted to rock the legs of a staple into parallel relation to its crossbar without deformation intermediate their ends to form a flat stitch.

Another object of the invention is to provide an implement of the type indicated wherein the stapling arm is held in raised position with respect to the work until a staple is driven to penetrate its legs through the work and thereafter moved toward the work to engage the ends of the projecting legs of the staple with camming grooves on the base of the implement.

Another object of the invention is to provide an implement of the type indicated having a sliding anvil with selective camming grooves formed therein for effecting a flat permanent stitch or a temporary pin-stitch.

Still another object of the invention is to provide an implement of the type indicated which is of simple and compact construction and proof against derangement or getting out of order.

Further objects of the invention are set forth in the following specification which describes one form of construction of the implement, by way of example, as illustrated by the accompanying drawings. In the drawings:

Fig. 1 is a side elevational view of a well-known type of implement incorporating the novel features of the present invention;

Fig. 2 is a part-sectional view similar to Fig. 1 showing the anvil yieldingly held in one of its two operative positions on the base to form a pin-stitch and the hand-lever depressed to drive a staple while the stapling arm is held in raised position with respect to the work;

Fig. 3 is a part sectional view similar to Fig. 2 showing the stapling arm depressed into engagement with the work to cause the legs of the driven staple to be clinched;

Fig. 4 is a front view of the implement with the parts shown in the same position as illustrated in Fig. 1;

Fig. 5 is a transverse sectional view taken on line 5-5 of Fig. 2 and showing the legs of the driven staple projecting from the stapling arm while the latter is held in raised position with respect to the work;

Fig. 6 is a view similar to Fig. 5 showing the

legs of the staple being rocked outwardly by the camming grooves in the anvil as the stapling arm is moved toward the base;

Fig. 7 is a view similar to Fig. 5 showing the stapling arm moved into engagement with the work and the legs of the staple rocked outwardly through an arc of ninety degrees to form a flat pin-stitch in the work;

Fig. 8 is a longitudinal sectional view through the clinching anvil and base of the implement showing the anvil yieldingly held in another operative position to aline a different set of clincher-grooves with the staple being driven;

Fig. 9 is a view similar to Fig. 6 showing the ends of the legs of a staple rocked inwardly by the camming grooves on the anvil as the stapling arm is moved toward the base;

Fig. 10 is a view similar to Fig. 9 showing the stapling arm moved into engagement with the work and the legs of the staple clinched in parallel relation to its crossbar to form a flat permanent stitch;

Fig. 11 is a transverse sectional view taken on line 11-11 of Fig. 8 showing the spring means for yieldingly holding the anvil in different positions on the base; and

Fig. 12 is a perspective view of the forward end of the base and anvil showing the structure of the parts to adapt the anvil to be detachably mounted on the base.

A standard type of desk stapler has a stapling arm embodying a magazine for the staples pivotally mounted on a base and staple-applying mechanism at the end of the arm adapted to cooperate with an anvil on the base. With this type of implement a spring is provided for holding the stapling arm raised with respect to the base to permit the work to be inserted therebetween. When the implement is operated the spring yields to permit the arm to first move toward the base to grip the work thereagainst and the driver is thereafter operated to drive a staple. As the staple is driven the ends of the legs are engaged by clincher-grooves in an anvil on the base and the clincher-grooves act to continuously bend and clinch the legs as they are driven.

It has heretofore been proposed to provide a device for first driving a staple through the work and thereafter rocking its straight projecting legs outwardly to form a flat stitch, but such previously used implements require special clinching means or other elements to cause the legs to be folded without deformation. In the Maynard United States Patent No. 1,506,073, is-

sued August 26, 1924, an arched spring-plate is mounted on the base and overlies the clinching anvil to hold the work suspended above the anvil until a staple is driven therethrough. After the 5 staple has been driven the force applied causes the spring-plate to yield to engage the ends of the staple-legs with camming grooves in the clincher-anvil. In the pending application of John F. Cavanagh, Serial No. 110,364, filed November 11, 1936, a work-supporter is pivotally mounted on the frame and is first operated to grip the work against the stapling arm and hold it suspended while a staple is driven therethrough. The work-supporter then yields to 10 cause the ends of the staple-legs to engage camming grooves in an anvil whereby to rock the legs into parallel relation to the crossbar to form a flat stitch.

in accordance with the present invention the 20 spring for holding the stapling arm in raised position with respect to the base is made sufficiently rigid to resist its movement toward the work until after the staple-driver has been actuated to drive a staple. In other words, the spring for holding the 25 stapling arm raised is more resistant than the spring for holding the staple-driver in raised position on the arm. After a staple has been driven the arm moves toward the work to engage the ends of the projecting legs of the staple 30 with camming grooves on the base to cause the legs to be rocked into parallel relation to the crossbar without deformation intermediate their ends. Another feature of the present invention is the provision of an anvil mounted to slide on 35 the base and having separate sets of camming grooves to adapt the implement to apply a staple to the work with either a permanent stitch or a temporary pin-stitch.

In its preferred form as herein illustrated the 40 invention is embodied in a fastener-applying implement of the type shown and described in Maynard United States Patent No. 2,037,334, issued April 14, 1936. Suffice it to state herein that the implement comprises a base 2, a stapling 45 arm 3 pivotally mounted on the base and an actuating lever 4 pivotally mounted on the arm and connected to operate a staple-driver 5. The base 2 is preferably constructed of sheet-metal stamped or embossed to form a generally flat, 50 rectangular top plate 6 bounded by a depending beveled flange 7. Fastened to the top plate 6 of the base 2 adjacent its rearward end is a hinge-block or mounting 8 for the stapling arm 3 formed with a hollow magazine for the staples s. The 55 stapling arm 3 is pivotally mounted on a pin 9 carried by rearwardly extending ears 10 on the hinge-block 8 with its ends projecting laterally through the depending sides of an inverted U-shaped member 11 attached to the bottom of the arm. The sides of the member 11 also overlie the sides of the hinge-block 8 on the base to prevent lateral twisting of the arm 3 with respect to the base.

The stapling arm 3 comprises a U-shaped member 14 having an inverted channel-shaped core 15 secured therein for supporting U-shaped staples s straddled thereacross. The forward end of the core 15 projects beyond the forward end of the member 14 and is provided with laterally offset, depending side flanges 16 having laterally projecting latching lugs 17 thereon. A channel-shaped member 18 is supported between the side walls of the member 14 with its bottom wall 19 overlying the core to hold the staples in place 70 thereon. The forward end of the core 15 is closed 75

by a U-shaped gate 20 having a front wall 21 which cooperates with the end of the core to provide a throat 22 therebetween and side walls 23 which overlie the sides of the core with notches 24 formed therein for cooperation with the lugs 17. The gate 20 is pivotally mounted on the member 18 by means of a pin 25 which extends transversely through oval slots 26 in the side walls of the member with its ends secured to the side walls 23 of the gate. Thus, the pin 25 may pivot on the member 18 to permit the front wall 21 of the gate 20 to be moved away from the end of the core 15 to open the magazine. Normally the gate is held in closed position as illustrated in Fig. 1 by the notches 24 in its side walls 23 yieldingly engaging with the lugs 17 on the depending flanges 16 of the core 15. A hairpin-shaped spring 27 tensioned between the arm 3 and pivot-pin 25 retains the notches 24 in engagement with the lugs 17. The staples s in the magazine are advanced along the core 15 toward the throat 22 by means of a pusher 28 and spring 29 connected thereto.

The staple-driver 5 is mounted to reciprocate in the throat 22 at the forward end of the arm 3 and is operated by the lever 4. The lever 4 is of inverted channel-shape having opposite sides 36 overlying the sides of the arm 3 and a front wall 37 overlying the forward end of the arm. The lever 4 is pivotally mounted on the arm 3 by means of a pin 38 extending transversely through the sides of the U-shaped member 18 and the sides 36 of the lever. Mounted on the inside face of the front wall 37 of the lever 4 is a block 39 having a tongue 40 which extends rearwardly through a suitable hole in the driver 5. The lever 4 is yieldingly held in raised position with respect to the arm 3, as illustrated in Fig. 1, by means of a relatively weak hairpin spring 41. At its forward end the lever 4 has a pad 42 to adapt it to be manually depressed against the action of the spring 41. Pivotally mounted between the sides of the U-shaped member 18 on the arm 3 is an element 43 which serves the double function of dogging the staples when the gate 20 is open and preventing a full return of the driver 5 until a full stroke has been completed, as more fully described in the Maynard patent referred to above. The arm 3 is also provided with a staple-supporter 44 which is mounted for combined pivotal and longitudinal movement to hold the crossbar of a staple s being driven against the bottom edge of the driver 5. As thus far described the implement is substantially identical with that illustrated in the Maynard patent referred to above.

In accordance with the present invention resilient means are provided for holding the forward end of the stapling arm 3 in raised position above the base 2 until the lever 4 has been depressed with respect to the arm to drive a staple s, the resilient means thereafter yielding to permit the arm to move toward the base. As herein illustrated, the means for holding the arm 3 elevated above the base 2 comprises a leaf-spring 50 attached to the base 2 and a plunger 51 acting between the spring and the under side of the arm, but it will be understood that other forms of yielding means may be provided as will appear to those skilled in the art. The leaf-spring 50 has one end attached to the under side of the top plate 6 of the base 2 by means of a screw 53 and extends rearwardly from its point of attachment. The plunger 51 has a head 56 which bears against the spring 50 below the top plate 6 and a shank-portion 54 which projects upwardly through a 70 75 80 85 90 95 100 105 110 115 120 125 130 135 140 145 suitable hole 55 in the top plate 6 of the base 2 with its end bearing against the under side of the member 14 of the arm 3. Thus, the plunger 51 has its opposite ends bearing against the spring 58 and the under side of the arm 3 adjacent the rearward end thereof to yieldingly hold the arm raised with respect to the base 2. The spring 58 of the present invention differs from springs heretofore used for a similar purpose in that it is made of such dimensions or of such material as to have a greater resistance than the spring 41 whereof to hold the arm 3 in raised position with respect to the base 2 until the driver 5 has been operated to drive a staple s.

15 Another feature of the present invention is the novel form of anvil 60 which is slidably mounted on the base 2 of the implement to selectively align one or the other of two separate sets of camming grooves 61 and 62 with the driver 5. The anvil 60 comprises a flat plate which overlies the top plate 6 at the forward end of the base 2 and is provided with laterally extending finger pieces 63 to facilitate sliding it from one to the other of its two positions. The 20 camming grooves 61 and 62 are in the form of slots cut into the top face of the anvil 60 and the two separate sets are spaced longitudinally thereof. The camming grooves 61 are adapted to rock the legs of a staple inwardly toward each other, the outer ends of the grooves being spaced apart a 25 distance substantially equal to the distance between the staple legs. The bottoms of the camming grooves 61 are continuously curved from the top face of the anvil at their outer ends inwardly toward each other and terminate in a 30 common apex 64 at the center. The camming grooves 62, on the other hand, are adapted to form a temporary pin-stitch by being arranged in longitudinally spaced relationship with their inner ends spaced apart a distance substantially equal to the distance between the staple legs. The bottoms of the camming grooves 62 are continuously curved from the top face of the anvil at their inner ends laterally outwardly and terminate at the top face of the anvil at their outer 35 ends.

40 Instead of curling the legs of a staple as it is being driven the camming grooves 61 or 62 of the present invention act to rock the legs of the staple about axes having a fixed relation to their points of joinder with the crossbar of the staple without substantially deforming the legs intermediate their ends. Therefore by the term "rock" as used herein and in the appended claims is 45 meant the swinging movement of the legs about axes which are relatively fixed in relation to the staple without substantial deformation intermediate the ends of the legs in contradistinction to the usual curled clinch caused by a continual deformation of the legs by the clincher-grooves while the staple is being driven.

45 The anvil 60 overlies a T-shaped slot in the top plate 6 of the base 2, the slot being formed by a relatively narrow portion 65 extending longitudinally of the base and a lateral portion 66 at the forward end of the narrow portion, see Fig. 12. A bridge 67 extends across the narrow portion 65 of the slot intermediate its ends, the bridge being of a width corresponding to the 50 space between the two sets of camming grooves 61 and 62 on the anvil 60 for a purpose as will appear later. The anvil 60 is provided with a depending flange 68 at its forward end of a length corresponding to the width of the forward portion 66 of the T-shaped slot and with a de-

pendent flange 69 at its rearward end of a width corresponding to the width of the narrow portion 65 of the slot. Thus, the relatively close fit of the flanges 68 and 69 in the slot-portions 65 and 66 holds the anvil 60 against twisting movement 5 on the base 2 while permitting relative longitudinal sliding movement thereof. The arrangement of the T-shaped slot on the base 2 is such as to align the camming grooves 62 with the driver 5 when the depending flange 69 is in engagement with the rearward end of the slot-portion 65 and to align the camming grooves 61 with the driver when the flange 68 is in engagement with the forward end of the slot-portion 66. The bottom of the anvil 60 is provided with a depending detent 70 having beveled sides which cooperate with the opposite sides of the bridge 67 extending across the narrow portion 65 of the T-shaped slot to detain the anvil 60 in one or the other of its two operative positions. 10

15 The anvil 60 is yieldingly held against the top plate 6 of the base 2 by means of a stud 74 which projects downwardly from the under side of the anvil through the narrow portion 65 of the T-shaped slot. A compression spring 75 mounted 20 on the shank of the stud 74 acts between a head 76 at the lower end of the stud and a washer 77 on the shank to press the latter against the bottom of the top plate 6 at opposite sides of the portion 65 of the slot, see Fig. 11. The anvil 60 thus constitutes a removable self-contained unit 25 which may be applied to the base 2 by sliding it rearwardly thereon while the washer 77 is depressed against the action of the spring 75 by any suitable tool to cause the shank of the stud to 30 enter the narrow portion 65 of the slot with the washer on the under side of the top plate 6 of the base. After the shank portion of the stud has entered the slot-portion 65 the depending flange 68 at its forward end engages the wider 35 portion 66 of the slot. The spring 75 acting between the washer and the head 76 of the stud yieldingly presses the anvil 60 against the top plate 6. The anvil may thereafter be easily slid to either one or the other of its two operative 40 positions. One form of the invention having now been described in detail its mode of operation is 45 as next explained.

45 The implement is first prepared for a staple-50 applying operation by sliding the gate 20 upwardly and then rocking it on its pivot-pin 25 to open the forward end of the magazine in the arm 3. A supply of staples s, preferably in the form of a stick, is then slid rearwardly onto the core 55 15 against the action of the pusher 28, the spring 29 yielding for this purpose. When released, the staples are held against movement outwardly of the magazine in the arm 3 by the element 43 until the gate 20 is rocked to its closed position to release the element. The staples s are automatically fed forwardly by the pusher 28 under the action of the spring 29 to position the foremost staple in the throat 22. If a temporary pin-stitch is to be formed the anvil 60 is slid rearwardly to position the camming grooves 62 in 60 alignment with the driver 5 and when a permanent stitch is to be made the anvil is slid forwardly to position the camming grooves 61 in alignment with the driver.

65 The work w is positioned in the opening between the anvil 60 and the staple-applying mechanism on the arm 3 and the pad 42 at the forward end of the lever 4 is then depressed. Due to the resistance of the spring 50 acting on the arm 3 by means of the plunger 51, the forward 70 75

end of the arm is held in raised position with respect to the base 2 until the driver 5 has been operated through a complete driving stroke to drive a staple s to pierce its legs through the work w in the manner illustrated in Figs. 2 and 5. Continued pressure on the lever 4 after the staple has been driven causes the spring 50 to yield and the forward end of the arm 3 to move toward the anvil 60. The engagement of the 10 ends of the legs of the staple s with the camming grooves 62 then causes them to be rocked outwardly without deformation intermediate their ends and the crossbar as illustrated in Fig. 6. This rocking movement of the legs of the staple s continues during the movement of the arm 3 toward the work until a pin-stitch is formed in the manner illustrated in Fig. 7. Due to the alignment of the laterally projecting legs of the staple substantially with its crossbar the stitch may be 15 easily and quickly removed in the manner of withdrawing a pin without mutilating or tearing the work. When the lever 4 is released the springs 41 and 50 act simultaneously to raise the lever and the driver 5 with respect to the arm 20 3 and to raise the arm with respect to the base 2.

When a permanent stitch is to be formed the anvil 60 is slid along the base 2 to align the camming grooves 61 with the driver 5. To slide the anvil 60 the laterally extending finger-pieces 63 25 are grasped between the finger and thumb and drawn forwardly on the base 2. Due to the inclination of the depending detent 70 the anvil 60 is cammed upwardly against the action of the spring 75 whereby it will ride over the bridge 67 during its forward movement until its depending flange 68 engages the end of the slot portion 66. The camming grooves 61 are then aligned with the driver 5 and the detent 70 is engaged with the opposite side of the bridge 67 to yieldingly 30 hold the anvil 60 in operative position on the base. With this adjustment the staple s is driven in the same way as explained above, the arm 3 being held in raised position with respect to the base 2 until the staple is driven and thereafter 35 moved toward the work to engage the ends of the legs with the camming grooves 61 as illustrated in Fig. 9. Continued movement of the arm 3 with respect to the base 2 causes the legs of the staple to be rocked inwardly toward each other without deformation intermediate their 40 ends and the crossbar to form a flat permanent clinch.

It will be observed from the foregoing that the present invention provides a construction and 45 arrangement of elements wherein the spring for holding the arm raised with respect to the base is more resistant than the spring for holding the driver in raised position on the arm whereby a staple may be driven through the work before its 50 legs are clinched. It will also be observed that the arrangement is such as to provide for rocking the legs about fixed axes to form a flat stitch instead of curling the legs during the driving of the staple. It will be observed further that the invention provides a novel form of anvil which is 55 slidable along the base to adapt it to selectively adjust one or the other of the spaced pairs of camming grooves in alignment with the driver whereby a flat temporary pin-stitch or a permanent 60 closed stitch may be obtained at the will of the operator.

While the device is herein illustrated as embodied in a preferred form of construction, it is to be understood that modifications may be made 65 in the structure and arrangement of its parts

without departing from the spirit or scope of the invention. Therefore, without limiting ourselves in this respect, we claim:

1. In a device of the type indicated, a base, an arm mounted on the base for movement toward and away from the latter, a driver on the arm for applying staples fed thereto, a spring for holding the driver in raised position on the arm, and a second spring of greater resistance than the first-mentioned spring acting on the arm rearwardly of the driver, said second-mentioned spring operating to hold the arm raised with respect to the work on the base until the driver has been actuated to drive a staple to penetrate its legs through the work and thereafter yielding to permit the arm to move toward the base. 5

2. In a device of the type indicated, a base, an arm pivotally mounted on the base for movement toward and away from the latter, a driver on the arm for applying staples fed thereto, a spring for holding the driver in raised position on the arm, a second spring of greater resistance than the first-mentioned spring acting on the arm rearwardly of the driver, said second-mentioned spring operating to hold the arm raised with respect to the work on the base until the driver has been actuated to drive a staple to penetrate its legs through the work and thereafter yielding to permit the arm to move toward the base, and camming means on the base adapted to be engaged by the ends of the projecting legs of the staple to rock them into parallel relation to the crossbar of the staple without substantial deformation intermediate their ends to form a flat 20 stitch. 30

3. In a device of the type indicated, a base, an arm pivotally mounted on the base, a driver on the arm for applying staples fed thereto, a lever pivotally mounted on the arm and connected to operate the driver, a spring for holding the lever raised with respect to the arm, a second spring of greater resistance than the first-mentioned spring acting on the arm rearwardly of the driver to hold the arm raised until the driver has been actuated to drive a staple to penetrate its legs through the work, and cam-slots on the base adapted to be engaged by the ends of the projecting legs of the staple to rock them into parallel relation to the crossbar of the staple without substantial deformation intermediate their ends 40 to form a flat stitch. 50

4. In a device of the type indicated, a base, an arm mounted on the base to adapt it to be moved toward and away from the latter, stapling mechanism carried by said arm including a staple-driver, a spring for holding the driver in raised position on said arm, a second spring of greater resistance than the first-mentioned spring acting on the arm rearwardly of the driver, said second-mentioned spring operating to hold the arm raised with respect to the work on the base until a staple has been driven to penetrate its legs through the work, and selective sets of camming grooves on said base for forming different types of stitches, said camming means being engaged by the ends of the projecting legs of the staple to rock them into parallel relation to the crossbar of the staple without substantial deformation intermediate their ends. 55 65

5. In a fastener-applying implement, a base having a slot adjacent one end with a bridge extending across the slot, an arm mounted on the base to adapt it to be moved toward and away from the latter, staple-applying mechanism on the arm, an anvil slidable on the base and hav- 70 75

ing separate sets of camming grooves for forming different types of stitches, said anvil overlying the slot in the base and having a detent intermediate its ends for cooperation with the opposite sides 5 of the bridge and flanges at its opposite ends depending into the slot, and resilient means for yieldingly holding the anvil on the base.

6. In a fastener-applying implement, a base having a T-shaped slot adjacent one end with a 10 bridge extending across the slot intermediate the ends thereof, an arm pivotally mounted on the base, staple-applying mechanism on the arm, a removable anvil slidable on the base and having separate pairs of camming grooves for forming 15 different types of stitches, said anvil overlying the T-shaped slot and having a detent intermediate its ends for cooperation with the opposite sides of the bridge and depending flanges at its ends cooperating with the ends of the slot to position one or the other of the pairs of camming 20 grooves in alignment with the staple-applying mechanism on the arm, a stud depending from the anvil through the slot in the base, and a

spring acting between the stud and the bottom of the base to yieldingly hold the anvil in place on the base.

7. In a device of the type indicated, an anvil adapted to support the work resting directly thereupon, fastener-applying means mounted for movement toward and away from the anvil, a driver incorporated in the fastener-applying means for driving fasteners fed thereto, a spring for holding the driver in raised position with respect to the fastener-applying means, a second spring of greater resistance than the first-mentioned spring for holding the fastener-applying means raised with respect to the anvil, said second-mentioned spring operating to hold the fastener-applying means raised with respect to the work on the anvil until the driver has been actuated to drive a fastener to penetrate its legs through the work and thereafter yielding to permit the fastener-applying means to move toward 15 the anvil. 10 15 20
